ABSTRACT

A positive displacement machine suitable for use with incompressible or compressible fluids as a pump, motor, compressor, or engine, operates on a continuous cycle and achieves either constant or varying volume of flow by both varying the distance of the fluid volume from the main axis of rotation of the machine and progressively continuously varying the volume of the chamber containing the fluid between the inlet and outlet of the machine.

**ROTARY MACHINE WITH ROTATING VANE
WHEELS CIRCULATING IN SPIRAL-LIKE
PASSAGES**

**BACKGROUND AND OBJECTS OF THE
INVENTION**

The present invention relates generally to liquid or fluid handling machines and relates more particularly to certain new and useful improvements in such machines having utility in pumps, motors, compressors and engines.

Pumps and Related Machines

With respect to the application of the invention with pumps, i.e., driving or driven liquid handling machines such as may be used for power transmission (hydraulic transmission), liquid transfer, and circulation under pressure, the invention is principally concerned with volumetric vane pumps in which the liquid, admitted through an inlet opening of a stator, is discharged by vanes of a rotor at an outlet opening.

In most current vane pumps, the stator is peripheral, the rotor is offset in relation to the stator, and the vanes are mounted for sliding movement in slots of the rotor. During the rotation of the rotor, the vanes undergo a reciprocating movement owing to their edges cooperating with the stator. In these constructions, the rotational speed is limited to a relatively small value because of the friction, particularly of the vanes in their guides which increases very quickly with the speed, and also because of the deterioration of the conditions under which the intake takes place.

A volumetric pump constructed according to the present invention overcomes these drawbacks and consists of a rotor having wheels regularly arranged about the axis of rotation thereof, each wheel being mounted for rotation about an axis perpendicular to its plane. For the discharge of the liquid to be put under pressure, the wheels have vanes which cooperate with passages in a stator, whose peripheral surfaces correspond to the paths of a part of the periphery of a vane during the composite movement resulting from the rotor rotation in relation with the stator as well as from the rotation of the vane wheel about the axis on which it is mounted. The covering of the passages is ensured by cooperation of the incurved surfaces of the stator adjacent to the passages with a mating cooperating surface of the rotor, from which the vanes of a wheel protrude for penetration into the passages.

Advantageously, the direction of rotation of a vane wheel about its axis corresponds to the path of a passage from its end nearest the rotor axis to that remote therefrom, the effect of centrifugal force being thus favorable to the intake of the liquid into the passage and discharge from the passage.

Each vane wheel advantageously comprises several vanes and the position in which a vane approaches a passage is strictly determined by another passage guiding another vane of the wheel cooperating with said other passage.

A rotor preferably includes several vane wheels disposed about its axis and at any instant a plurality of vanes circulate in the passage of the stator.

Owing to the total absence of alternative movements and to excellent suction conditions, a pump according to the invention can turn at extremely high speeds.

The discharge of the pump is regular, thus avoiding the need for accessories that are frequently provided to control the flow at the outlet of the vane pump.

The construction provides radial balancing, so that high pressures can be reached without difficulty.

According to a preferred embodiment, a generally disshaped rotor operates on both faces, each face supporting a series of vane wheels. The combination is thus axially balanced without using special means.

10 The present invention relates not only to driven machines functioning as pumps, but also to machines functioning as motors, the liquid exerting a force on the vanes housed in the passages, which, by means of the wheels, puts the rotor carrying them into rotation.

Compressors

Turbo-compressors, such as the axial or centrifugal compressors, as well as the volumetric compressors, such as the piston, vane or other compressors, have 20 drawbacks which heretofore have not been possible to overcome.

Turbo-compressors, in spite of their high rotational speed, which requires large, bulky speed-reducing gear, do not enable high compression ratios to be obtained.

25 In most cases, the compression has to be performed in several stages. Furthermore, the efficiency of turbo-compressors is acceptable only in a relatively narrow range of proportion of compression ratio versus inlet flow rate.

30 The piston compressors, which are advantageous from the point of view of compression ratio, are too slow, bulky, heavy and noisy, owing to the reciprocating movement of the constituent parts. Previously known vane compressors which are compact, have

35 major drawbacks relating to the freedom in the housing of the vanes in the rotor passages and to the asymmetry of the radial thrusts exerted on the rotor. Owing to the effect of centrifugal force on the vanes, the friction is great. The reciprocating movement of the vanes in their passages, does not permit high rotational speeds, speeds which cause unsatisfactory filling and mechanical efficiency.

A vane compressor constructed according to the invention enables better performances than those of the existing vane gas compressors from the point of view of rotational speed and flow rate, as well as from the point of view of compression ratio.

Not only is the friction due to the centrifugal forces minimized, but reciprocating parts are eliminated. Such a machine is fast, compact and quiet, allowing high compression ratios.

The invention relates to a driven machine for compressible fluids or gas compressor, as well as driving machine, although the description herein below refers only to driven machines or gas compressors for simplification.

60 The present invention thus also consists in a gas compressor having a rotor comprising wheels regularly distributed about the axis of rotation thereof, each wheel being mounted for rotation about an axis which is perpendicular to its plane. The said vane wheels include vanes cooperating with passages of the stator for the compression of the gas, their peripheral surfaces corresponding to the path of a portion of the periphery of a vane during the combined movement resulting from the rotor rotation relative to the stator, as well as the rotation of the vane wheels about the shafts on which

they are mounted. The covering of the passages is effected by the cooperation of the incurved surfaces of the stator adjacent to the passages with a complementary surface on the rotor, from which the vanes of a wheel extend into the passage.

In a preferred embodiment, the direction of rotation of a vane wheel about its axis corresponds to the path of a passage from its end nearest the rotor axis to its end remote from the axis. In an alternative embodiment, the vanes pass through the passages from the periphery towards the center. Each wheel comprises several vanes and the position of a vane approaching a passage is strictly determined by another passage guiding another vane of the wheel with which it cooperates.

A rotor preferably includes several vane wheels disposed about its axis and at every moment a plurality of vanes circulate in the passages of the stator.

Owing to the total absence of reciprocating movements and to excellent suction conditions, a compressor constructed according to the invention may turn at extremely high speeds.

According to a preferred embodiment of the invention, a generally disc-shaped rotor operates on both faces, each carrying a series of vane wheels.

Engines

In most current thermal engines, the working fluid or operating medium is first compressed, a certain quantity of heat is introduced therein, in most cases by combustion, and the expansion of hot gases supplies the useful work.

In volumetric engines of the piston type or rotary piston type, the operation is non-continuous, which does not permit a complete combustion nor high compression ratio to be obtained, which is necessary to obtain high efficiency in the heat cycle as well as a high power-to-weight ratio. Furthermore, the reciprocating movements of numerous parts and the explosive nature of the combustion lead to heavy, bulky, noisy and polluting engines.

In the engines known as gas turbines, the heat cycle is continuous, but its various phases call for distinct features: the compression takes place in axial or centrifugal compressors, the combustion in a combustion chamber and the expansion is achieved in either axial or centrifugal turbines.

In gas turbines, while combustion is substantially complete, only machines in which the compressor as well as the turbine comprise several stages, thus being complicated to manufacture and expensive to build, can attain high compression ratios.

Regarding small and medium power machines, previously known gas turbines have relatively low efficiencies and power-to-weight ratios, less than volumetric engines and are not well adapted to power vehicles, due to their lack of flexibility and braking capacity.

In a gas engine constructed according to the present invention, the expansion of hot gases takes place in spiral-like passages of the stator, said gases acting upon vanes sealingly cooperating during displacement in spiral-like passages, and forming part of the wheels mounted for rotation in a rotor coaxial to the stator, the mechanical energy being picked up on its shaft. The sealing of the spiral-like passages is provided by cooperation of the curved surfaces of the stator with those of the rotor.

The present invention thus relates to an engine in which the compressed air admitted into a combustion chamber is supplied by a compressor, comprising a stator with spiral-like passages cooperating with the vanes

5 of rotary wheels of a rotor, the shaft of the rotor being driven by the shaft of the engine. The sealing of the spiral-like passage is ensured by the cooperation of curved surfaces of revolution of the stator and those of the rotor.

10 In a preferred embodiment of the invention, the vane wheels cooperate, during a part of the path of movement of their vanes, with the spiral-like passages of a first stator, which compresses the air, and during another part of the path of movement the vane wheels co-

15 operate with the spiral-like passages of a second stator, which is supplied with hot gases produced by the combustion in which the previously compressed air has participated, the vane wheels being thus part of a compressor as well as part of a gas turbine.

20 The engine according to the present invention has all the advantages of current volumetric engines and the gas turbines without their drawbacks.

Being in principle a volumetric machine, the present engine achieves continuous high compression ratios in 25 a single stage without using any reciprocating movement.

30 The temperature of the gases admitted into the present turbine may be higher than in the current gas turbines, owing to better possibilities of cooling the stator and the rotor as well as to smaller forces exerted on the rotor.

35 As the combustion is continuous, the engine is highly efficient with a high power-to-weight ratio and flexibility being thus particularly well adapted to power vehicles. Substantially complete combustion is obtained at high compression ratios so that the pollution production per unit of work output is much smaller than in current heat engines. In addition, it operates at a very low noise level, making it particularly suitable for meeting strict regulations for the protection of the environment.

40 The engine according to the present invention may work either in an open or closed circuit.

45 Objects and advantages of the invention are set forth in part herein and in part will be obvious herefrom, or may be learned by practice with the invention, the same being realized and attained by means of the instrumentalities and combinations pointed out in the appended claims.

50 The invention consists in the novel parts, constructions, arrangements, combinations and improvements herein shown and described.

SUMMARY OF THE INVENTION

55 Briefly described, the present invention relates to a positive displacement machine having utility as a pump, motor, compressor or engine.

60 In the preferred embodiment, there is provide a stator member on which there is formed a plurality of spaced, spiral-like ribs defining an equal number of spiral grooves therebetween, the ribs emanating at equal circumferentially spaced intervals about the periphery of the stator. A rotor member is rotatably mounted coaxially of the stator and is provided with a plurality of 65 relatively thin slots preferably extending normal to the axis of rotation of the rotor, each slot carrying a vane wheel mounted for rotation about an axis which is inde-

pendent of the axis of rotation of the rotor member. Each vane wheel is comprised of a plurality of vane members which protrude from the forward face of the rotor and are adapted to be slidably sealingly received in the spiral groove portions of the stator for circulation therein upon rotation of the rotor. The forward face of the rotor member is provided with a convexly curved annular portion which is adapted to cooperate with, and sealingly engage, a mating annular concave surface defined on the outer edges of the spiral ribs formed on the stator. When the rotor and stator are mounted in sealing, mating engagement, the convexly curved front annular portion of the rotor defines with the bottom of each of the spiral grooves, an enclosed channel which is of a continuously varying depth either progressively increasing or progressively decreasing, from the central opening to the outer periphery of the stator.

Heretofore, the ratio and gradient or rate of compression or expansion of the fluid in rotating vane machines has always been obtained solely by reason of the translational velocity change imposed by the difference in radii at which the vanes are located in their movement from the inlet to the outlet with respect to the axis of the rotor. The amount of the change in compression or expansion obtainable with machines of this construction is thus limited by the available physical dimensions for the machine. These previously known constructions are also limited in their usage, since the compression inlet must always be at the greater diameter and the outlet for the compressed gases at the smaller diameter and, similarly, the inlet for expansion must always be at the smaller diameter and the outlet of the expanded gases at the greater diameter due to the difference in volume of compressible fluids. Further, such a structure cannot be operated as a pump since the spiral vanes impose a built-in compression gradient on the fluid flowing therethrough and a pump must have a constant volume rate of flow.

The continuous progressively varying depth of the spiral grooves in the construction of the present invention provides an additional parameter for changing both the ratio and gradient or rate of compression or expansion, permitting high compression or expansion ratios to be obtained, and at desired rates, which have not heretofore been available in rotating vane machines without the use of expensive and complicated machinery. Also, by providing the rotatably mounted vane wheels in the rotor member and the spiral-like passageways in the stator member, the construction of the invention has great versatility of use, either as a positive displacement turbine, pump, compressor, or hydraulic motor, or in combinations of the foregoing and in single or double stages. Further, in any of the foregoing uses of the invention, the inlets and outlets for compression or expansion are not limited to any particular diametrical position in the machine.

In an exemplary embodiment of the invention which is of particular interest, a pair of rotor members are mounted in spaced relation to one another on the same shaft, each in operative association with a stator member constructed as previously described. A gas introduced into the first stator is compressed by the vane wheels of the compressor rotor circulating therein and thereafter fed to an intermediate combustion chamber where the compressed gas is mixed with a fuel and ignited. The gases of combustion expand into the spiral passageways of the second stator, pushing against the

vane wheels of the turbine rotor circulating therein to thereby drive the turbine rotor and, hence, to also drive the compression rotor.

In an alternative construction for a combined turbine and compressor, a single rotor member is provided in which the back face is constructed in the same manner as the previously described front face thereof, and is mounted in operative association with a compressor stator on one side and a turbine stator on the outer side. 10 In this construction, the vane wheels compress the incoming gas on one side of the rotor and are, in turn, driven by the expanding gases of combustion on the other side of the rotor, to thereby drive the rotor.

It will be understood that the foregoing general description and the following detailed description as well as are exemplary and explanatory of the invention but are not restrictive thereof.

The accompanying drawings, referred to herein and constituting a part hereof, illustrate preferred embodiments of the invention, and together with the description, serve to explain the principles of the invention.

DESCRIPTION OF THE DRAWINGS

FIG. 1 is a view, partly in elevation and partly in axial section, of a positive displacement fluid or liquid handling machine constructed according to the invention;

FIG. 1a is a schematic view of a combined compressor and gas engine constructed according to the present invention;

FIG. 2 is a view of a rotor on the face opposite to that from which the vanes extend;

FIG. 3 is a view in section along line 3-3 of FIG. 2;

FIG. 4 is a view in section along line 4-4 of FIG. 3;

FIG. 5 is an enlarged view in side elevation of a vane wheel;

FIG. 6 is a view in section along line 6-6 of FIG. 5, but on a greater scale;

FIG. 7 is a view similar to FIG. 6, but for an alternative embodiment;

FIG. 8 is a view in section along line 8-8 of FIG. 5, but on an enlarged scale;

FIG. 9 is a schematic view in perspective of a stator and a rotor separated from each other;

FIG. 10 is a front view of the stator;

FIG. 11 is a fragmentary view in section showing a passage of the stator covered by the rotor;

FIG. 12 is a schematic view on an enlarged scale of cooperating parts of the rotor and the stator;

FIG. 13 is a schematic diagram of developed flanks or sidewalls of a passage;

FIG. 14 is a schematic diagram of a developed flank or sidewall of a passage;

FIG. 15 is a fragmentary view in section on an enlarged scale of a sealing means between the stator and the rotor;

FIG. 16 is a fragmentary view in perspective of part of a vane wheel according to an alternative embodiment;

FIG. 17 is a view in cross-section of the vane illustrated in FIG. 16;

FIG. 18 is a fragmentary view in perspective of a vane according to another alternative embodiment;

FIG. 19 is a schematic front view of a vane wheel system for another alternative embodiment;

FIG. 20 is a fragmentary view in profile, developed and on an enlarged scale of the vane wheel of FIG. 19;

FIG. 21 is a fragmentary schematic diagram showing

the vane wheel system of FIGS. 19-20 with the stator; FIG. 22 is a schematic front view of a rotor illustrating an alternative configuration of vane wheels;

FIG. 23 is a view in axial section of an alternative embodiment of a machine according to the invention;

FIG. 24 is a fragmentary, enlarged view of two cooperating vane wheels, for the embodiment of FIG. 23;

FIG. 25 is a view similar to FIG. 23, illustrating another embodiment of a machine constructed according to the invention;

FIG. 25a is a view similar to FIG. 25, illustrating the operation of the machine as a gas turbine;

FIG. 26 is a cutaway schematic view of the stators with passages and the rotor with vane wheels for the embodiment of FIG. 25;

FIG. 27 is a view similar to FIGS. 23 and 25, but for still another alternative embodiment thereof;

FIG. 28 is a schematic view of the stator with passages and the rotor with vane wheels for the embodiment of FIG. 27;

FIG. 29 is a schematic view in axial section for still another alternative embodiment;

FIG. 30 is a view in elevation, partly sectional, of a construction according to the invention, embodied as a compressor;

FIG. 31 is a view in elevation, partly sectional and partly schematic, illustrating a compressor constructed in accordance with the invention having several stages;

FIG. 32 is a schematic view of an assembly of a gas turbine and a compressor, constructed according to the invention;

FIG. 33 is a view similar to FIG. 32, illustrating an alternative embodiment thereof;

FIG. 34 is a fragmentary schematic view of an alternative embodiment of a compressor constructed according to the invention;

FIG. 35 is a view similar to FIG. 32, illustrating a further alternative embodiment thereof;

FIG. 36 is a view in section along an axial plane of a rotor for a further alternative embodiment thereof;

FIG. 37 is a partial view in section along a transverse plane, on a larger scale, of the rotor shown in FIG. 36;

FIG. 38 is a view similar to FIG. 25, illustrating another embodiment of a machine constructed according to the invention, in which there are provided two rotors and four stators; and

FIG. 39 is a view similar to FIG. 25, illustrating a floating stator member spring-biased into engagement with vane wheels mounted in the rotor member.

DESCRIPTION OF THE PREFERRED EMBODIMENTS

Referring now more particularly to the accompanying drawings, the positive displacement machine of the invention comprises a stator 20 (FIG. 1), with a cylindrical body 21 spreading out into a disc 22. The cylindrical body 21 has an axial bore 23, which receives a tube or pipe 24 for fluid intake to be put under pressure when functioning as a compressor, and for liquid intake to be discharged under pressure when the machine functions as a pump. Beyond a shoulder 25, the surface 26 of the bore 23 extends the internal surface of the pipe 24 and flares out into a truncated coneshaped inlet 27 for a chamber 28 disposed between the stator 20 and a casing 29 which houses a rotor 30.

The assembly of the engine comprises a compressor 511 and an engine per se 512 (FIG. 1a) which are similar constructions.

The casing 29 coaxial to the stator 20 is secured to the latter by means of bolts 31 extending through holes 32 in the stator 20 cooperating with tapped bores 33 in the casing 29. The external surface of the casing 29 extends the external surface of the stator, and the casing 29, which is disc-shaped, extends into a cylindrical body 35 coaxial to the stator body 21.

The casing 29 has an incurved interior surface 36 providing an annular discharge compartment 37 which may be formed as a volute in which a bore 38 begins and continues towards the exterior by a discharge pipe or tube 39. The incurved internal surface 36 of the casing 29 is extended by a flat surface 41 facing directly opposite the flat surface 42 of a generally cylindrical body 43 (FIG. 2) of the rotor 30. The body 43 is fixed to a rotor shaft 44, located in the casing 29 by means of a bearing 45 in a recess 46 in the body 35 of the casing 29.

The interior surface 47 (Fig. 3) of the rotor body 43 opposite and parallel to the exterior surface 42 is set against the flat face 48 of a rotor disc 49, the body 43 being assembled with the disc 49 by bolts 51 received in holes 52 of the body 43 and cooperating with tapped bores 53 in the disc 49.

As best seen in FIG. 2, four diametrical slots, 56₁, 56₂, 56₃, 56₄, regularly angularly distributed about the axis 57, which is common to each of the rotor 30, the stator 20 and the casing 29, extend across the assembly formed by the body 43 and the disc 49. These slots are defined by parallel flat surfaces 58, 59 parallel to the axis 57 and symmetrically arranged on each side of a median plane 61 passing through the axis 57.

Each of the slots 56 houses a relatively thin vane wheel 62, its parallel flat faces 63 and 64 directly opposite the flat faces 58 and 59 of the slot 56 (FIG. 4), the wheel 62 rotating about an axis 71 by means of a smooth bearing 65 by which it is mounted for free rotation in the rotor body 30.

A vane wheel 62 preferably comprises eight vanes 69 regularly angularly distributed about the axis 71 (FIG. 5) of the wheel. The vanes 69 are most simply formed by peripheral cut-outs or teeth in the wheel 62. Each vane is defined by longitudinal sides 72 and 73 and a front side 74.

In the embodiment illustrated in FIG. 5, the sides 72 and 73 are linear and parallel to the center line 75 of the vane going through the axis 71; the side 74 is arcuate, advantageously comprising an arc of the circle 76 centered on the axis 71.

Intertooth spacings 78, defined by the bottoms 79, are formed between the teeth 69.

The longitudinal sides 72 and 73 of a vane 69 are preferably rounded, as is shown by the curved lines 81 and 82 in FIG. 6.

In an alternative embodiment shown in FIG. 7, the sides 72, 73 are bevelled, as shown by inclined planes 83, 84 and 85, 86, from each side of edges 87 and 88, respectively.

The front sides 74 of the vanes 69 are also advantageously rounded, as shown in FIG. 8 at 89.

The diameter of the vane sheets 62, i.e., the circle 76, is large enough so that the vanes extend from the interior front surface 77 of the rotor disc 49, the one opposite the surface 42.

The operating surface of the stator 20 facing the rotor 30 includes an annular part 90 cooperating with the casing 29 which is provided with four spiral-like passages 91a, 91b, 91c, 91d (see FIGS. 9 and 10), which are identical to one another and are regularly angularly distributed about the axis 57 common to each of the stator 20, the casing 29 and the rotor 30.

The inlets 92a-92d of the passages 91a-91d, respectively, are situated along a circle 93 wherein the opening of the flared portion 27 terminates, and the outlets 94a-94d of the passages 91a-91d, respectively, are situated along a circle 95 formed on the surface 90 of the stator 20 cooperating with the casing 29.

A typical passage 91a of the stator is illustrated in FIG. 11. It is defined by a bottom 96, an interior flank or sidewall 97 nearest to the axis 57 and an exterior flank or sidewall 98 farther from the axis 57 than the interior flank 97, which coincide with the paths of the different points on the periphery of a vane. The movement results from the combination of the rotation of the rotor 30 about the axis 57 and the rotation of the wheel 62 with the vane about the axis 71 of the wheel.

During the rotation of the rotor 30 powered by its shaft 44, the side 73 cooperates with the exterior flank 98 of the passage 91a as the vane 69 of a wheel 62 approaches the passage. As the rotating movement of the rotor 30 continues, the wheel 62 continues to rotate about its axis 71, the side 73 following a path which is that of the exterior flank 98 of the passage 91a. The front side 74 describes the bottom 96 of the passage and the side 72 of the vane 69 describes the path of the interior flank 97 of the passage 91. At the outlet of the passage 91a, the side 73 of the vane 69 first leaves the exterior flank 98, then the front side 74 progressively slips away from the bottom 96 of the passage as its different parts cross the circle 95, and finally, the side 72 of the vane 69 slips away from the interior flank 97 of the passage.

The exterior flank 98 of a passage, for example the passage 91a, and the interior flank 97 of the passage in the direction opposite the rotation of the rotor, in this case the passage 91d, defines a rib 101a-d thus placed between two passages. The top faces 102 of the ribs 101 are part of an incurved surface, mating with the operating surface 77 of the rotor 30. That operating annular surface 77 is wide enough to be in contact with the various top surfaces 102 of the various ribs 101 with which it is in tight sliding cooperation.

The operating surface 77 is part of a surface of revolution generated by a curve 103 (FIG. 12) having ends 104 and 105 rotating about the axis 57. The bottoms 96 of the passages 91a-91d are part of the surface of a torus of axis 57 generated by the rotation of an arc of a circle 76 about the axis 57, the center 71 of the circle being that of the axis of a wheel 62. When operating as a pump, the contour and the positioning of the curve 103 are so chosen that the operating surface 77 and the torus 76 define passages 91a-91d whose depth, that is the distance measured parallel to the flanks between the bottom 96 of the passage and the part facing the operating surface 77 of the rotor, is inversely proportional to the distance of the cross section to the rotational axis 57 of the rotor.

Reference is now made to FIG. 13, which shows a developed exterior flank of a typical passage. The exterior flank 98 of a passage such as 91a, joins the bottom 96 along an edge 151. It joins the top face 102 of the

rib 101 along an edge 152. The inlet side 153 starts along the circle 93. The height of the flank, which is maximum at the inlet, where it is equal to the length of the edge 153, progressively decrease to the peripheral outlet along the circle 95 where it is equal to the length of the edge 154 which connects the end 155 of the upper edge 152 with the end 156 of the lower edge 151.

The interior flank (FIG. 14) of the same passage 91a starts along the circle 93 at a point 157 at an angular distance from the point where the side 153 starts and is defined by a side 159, by the junction edge 161 with the bottom 96 and by the junction edge 162 with the top surface 102 of the rib 101. The height of the flank 97 may be considered equal to the length of the segments parallel to the rim 159, and having their ends on edges 162 and 161, respectively. This height constantly decreases from the interior side 159 of the flank to its exterior side 163. However, the contour of the interior flank 97 is substantially identical to that of the exterior flank 98.

The effective portion of each of the passages 91a-91d in which the vane 69 drives the fluid is that in which the two longitudinal edges 72 and 73 of the vane cooperate with the interior flank 97 and the exterior flank 98. In FIG. 13, showing the developed profile of the interior flank, the effective portion is between the two lines 164 and 165 passing through the side 159 of the interior flank 97 and the side 154 of the exterior flank 98.

In the effective or working portion of the passage, the rate of fluid flow driven by the vane may be considered at any moment as proportional to the height of the curve 166 shown in dotted lines, its ordinates being the averages of the ordinates of the curve 152 and the curve 162. At any moment, the rate of fluid flow driven by a vane in a passage is also proportional to the speed with which the vane 69 moves inside the passage, and thus, for a constant angular speed of the rotor shaft 44, it is proportional to the distance of the vane from the rotor's axis 57. The curve 103 generating the surface of revolution on which are placed the top surface 102 of the ribs 101 and cooperating with the surface 77 of the rotor 40, is chosen such that, at each point of the curve 166, the product of the ordinate, of that curve (this ordinate being the average of the ordinates of the points on the same abscissa of the curves 152 and 162) and the linear speed of the vane at said point is constant when the machine operates as a pump and advantageously progressively decrease as the curve extends from its origin to its end, that is, from left to right in FIG. 13 when the machine functions as a compressor or a turbine. The compression ratio obtained is higher if the fall is sharper.

As soon as the vane 69 enters a passage, such as 91a, the longitudinal side 73 cooperates first with the exterior flank 98, the longitudinal side 72 not as yet being in the passage, the front side 74 being located on both sides of the circle 93 from which the bottom 96 extends. After the side 72 has reached the interior flank 97, the vane 69 separates from the chamber 28 the downstream part of the passage 91a due to the cooperation of the sides 72, 73 and 74 of the vane 69 with the interior flank 97 and exterior flank 98 and the bottom 96 of the passage, respectively, due to the cooperation of the arch-shaped portion overhanging the passage and part of the operating surface 77 of the rotor with the top surfaces 102 of the ribs 101 defining the pas-

sages, and also to the fact that the vane wheel 62 is mounted with minimal clearance in the radial slot of the rotor. The vane 69 continues circulating in the passage 91a, its front side 74 cooperating with the bottom 96, its side 73 cooperating with the exterior flank 98 and its side 72 being in contact with the interior flank 97, by pushing the liquid or fluid forward until the longitudinal side 73 leaves the exterior flank 98. This corresponds to the part of the curve 162 of FIG. 13 situated on the right of the dotted line 165, the vanes 69 in the last part of its path only being in contact with the bottom 96 by a progressively decreasing portion of its front side 74 and with the interior flank 97 by its side 72, until the moment when the latter reaches the circle 05 and the vane 69 completely leaves the passage 91 of the stator 20.

As a vane, for instance the vane 69_{1B}, of a wheel 62 (FIG. 9), for instance the wheel 62_B, cooperates with the passage 91a the wheel 62_B rotates around the axis 71 and the vane 69_{2B}, following the vane 69, in a direction opposite to the rotation of the wheel 62, approaches the operating surface of the stator 20. It reaches said operating surface at the start 92b of the passage 91b when the plane of the wheel 62 comprising the vanes is approximately in the position shown in dotted lines in FIG. 9, exactly in the same position as the vane 69_{1B} reaching the operating surface of the stator at the start 92a of the passage 91a.

The passage 91b cooperating with the vane 62_{2B} is identical to the passage 91a, the cooperation of the vane 69_{2B} is identical to the passage 91a, the cooperation of the vane 69_{2B} with the passage takes place under the identical conditions to those described above for the cooperation of the vane 69_{1B} with the passage 91a.

Before the vane 69 of the wheel 62_B leaves the passage 91a, a vane 69_{1A} of the wheel 62A, following the wheel 62_B, reaches the passage 91a under exactly the same conditions as the vane 69_{1B} of the wheel 62_B in said passage.

While the vane 69 is moving forward in a passage, such as 91a, the liquid or fluid contained in the passage is discharged by the advancement of the vane when the latter reaches a point in the passage where its longitudinal side 72 cooperates with the interior side 97; the vane 69 sealingly progresses in the passage, that is, apart from leakage, not allowing the liquid or fluid either to flow back between the longitudinal sides 72 and 73 and the interior and exterior flanks 97 and 98 of the passage, respectively, or between the front side 74 of the vane 69 and the bottom 96 of the passage, or allowing the liquid or fluid to escape by crossing the top faces 102 of the ribs 101 along the passage with which cooperates the operating surface 77 of the rotor 30.

When two vanes 69 of two successive wheels cooperating through their longitudinal sides with the interior and exterior flanks or sidewalls of the passage are in the same passage at sections spaced angularly by 90° around the axis 57 of the rotor, the liquid or fluid behind or upstream of the first vane is pushed forward by the second vane. When operating as a pump or liquid motor, the space left by the first vane in the passage during its movement is constantly equal to the volume pushed in the passage by the second vane, owing to the equality of volumes driven by the vanes through the passages in spite of different tangential speeds depending upon the distance from the rotor axis resulting from the spiral-like shape of the passages, because of the

varying depth of the passages resulting from the profile of the arch, as previously discussed.

The liquid is thus evenly discharged, without water hammer or local depression. The liquid or fluid discharged by the vanes, cooperating with the passage closest to their outlets, escapes through the external outlet 94 and thus is discharged under pressure in the space 37 and towards the exterior by the pipe 39.

In the case where the machine is to be utilized as a compressor, gas motor or turbine, and the fluid is to be compressed space left by the first vane during its movement is, at every moment, smaller than the volume forced in the passage by said second vane, due to the variation in the passages' depth, given the different linear speeds of the vanes which vary with their distance from the rotor axis according to the spiral configuration of the passages' course, where the fluid is to be expanded, the aforementioned space is greater at each moment.

The gas is thus evenly compressed and discharge under pressure in the duct 39.

The loss of pressure introduced by the very small space existing between the flat face 42 of the rotor 30 and the flat face 41 facing the casing 29 is sufficient to enable sealing means of simple construction to be used in order that the shaft 44 of the rotor 30 extends through the casing 29.

A manifold may collect the liquid or fluid that reaches the annular space between the shaft 44 and the body 35 of the casing 29 and return this liquid either to the inlet tube 24 or any point along the fluid circuit before being put under pressure.

In an alternative embodiment, a plate is introduced in each slot 56, with one side extending the surface 42 of the rotor body, one side resting on the shaft 44 and one curvilinear side, as shown by the dotted line 54 in FIG. 1, within a short distance of the path of the front sides 74 of the vanes of the wheel housed in the slot.

In the embodiment of FIG. 15, a groove 315 houses a similarly shape seal 316 with a slight clearance, the groove being on the top surface 311 of a rib 312 with passages on each side. Under the action of resilient means, such as a spring shown schematically, at 317, the outer surface 318 is urged against the operating surface 319 of the rotor 320, thus aiding the sealing of the compartments defined by the vanes in the passages 313 and 314 during their movement.

Reference is now made to FIGS. 16 and 17. In this embodiment, a vane wheel 331 is constituted by two half cooperating vane wheels 332 and 333, each comprising half vanes 334 and 335, respectively, overlapping a few degrees, the thinned parts 336 and 337 providing surfaces 338, 339, 340 and 341, between which are disposed springs, shown schematically at 342 and 343. The vane 344, resulting from the joined half-vanes 334 and 335, has the profile of a vane as previously described, however, with longitudinal sides 346 and 347 maintained under pressure against the exterior and interior flanks of a passage by the action of springs 342 and 343.

The invention also relates to an embodiment in which the stator itself tends to ensure the sealing between the rotor and the stator, the latter being mounted free to move longitudinally in a stator body, resilient or hydraulic means being provided to push the stator against the rotor.

In the embodiment of FIG. 18, a vane 431 has longitudinal sides 432 and 433 connected to the front side 434 by rounded portions 435 and 436. It is thus possible to house in a groove 437 of the edge of the vane a filiform sealing system 438, which tends to elastically move away from the vane body by cooperating with the interior and exterior flanks as well as the bottom of the passage; thus providing a cooperation similar to that obtained by the ring on a piston of an engine cooperating with a cylinder.

The rotor and the stator are advantageously assembled with the side of the rotor comprising the operating surface 77 facing the operating surface of the stator, with the rotor axis extending along the stator axis. When the rotor is in such an angular position relative to the stator that the planes of the wheels 62 are perpendicular to the parts of the center lines of the passages 91 that they cross, vanes 69 of the wheels may be easily received in the passages 91. It is then possible to arrange the casing 29 in such a way that it encloses the rotor 30 and to then join up the casing 29 and the stator 20 with bolts 31.

Reference is now made to FIGS. 19 to 21. In this embodiment, the machine comprises a vane wheel system 901 resulting from the bringing together of two wheels 902 and 903, the wheel 902 has vanes 904 regularly off-set and separated by spaces 905, substantially of the same angular separation. The wheel 903 having the same configuration as the wheel 902 is angularly displaced from the latter, so that its teeth 906 face spaces 905 in the wheel 902, the spaces between the teeth 906 facing the teeth 904 of the first wheel.

The stator of a machine comprising such vane wheels systems has relatively thin top faces 102. FIG. 21 shows schematically a vane 904 cooperating with the passage 91b and a vane 906 cooperating with the passage 91a.

In the embodiment of FIG. 22, the planes of the vane wheels 421, instead of being radially oriented, that is, passing through the rotor axis, are inclined so as to be tangent to a circle 422 having its center along the axis so that the angle that the plane of a vane circulating in a passage 91 makes with the tangent to the center line 423 of the passage 91 is constantly of sufficient width. The cooperation of the longitudinal sides 72 and 73 of the vanes with the flanks 97 and 98 of the passage is always excellent. This embodiment is of particular interest when there are a great number of passages 91 on the stator 20 in order to obtain a high flow rate.

The pump according to the invention has a particularly high output. It functions without vibrations, perfectly smoothly, with constant pressure and discharge which are characteristics not previously known in vane pumps. Similarly, the compressor according to the invention has a particularly high output. It functions without vibrations, perfectly smoothly, and with constant pressure and discharge, characteristics which are unknown in current vane compressors.

In an alternative embodiment, the vane wheels cooperate with a first stator as in the embodiment described and with a second stator symmetrically disposed relative to the first one in relation to the plane of the axes of rotation of the vane wheels. The inlet of the second stator receives liquid or fluid discharge from the first stator, and the machine thus constitutes a two-stages pump or compressor with one set of vane wheels.

Reference is now made to FIGS. 23 and 24. In this embodiment, a rotor 200 comprises an annular body

201 in which one of its front faces 202 cooperates with a first stator 203 and its other front face 204 cooperates with a second stator 205, the rotor 200 being symmetrical in relation to the median transverse plane 206. The 5 rotor 200 has on one side of the median plane 206 a first series of vane wheels 207 and on the other side of the median plane 206 a second series of vane wheel 208, the vane wheels of both series being mounted in common slots 214 of the rotor. A vane wheel 207, 10 mounted for rotation about its axis 209, meshes with a vane wheel 208 mounted for rotation about its own axis 210. In this embodiment, the intertooth spacing defined by the opposed longitudinal sides 211 and 212 (FIG. 24) of the vanes or neighboring teeth is at least 15 equal to the width of a tooth, that is, the distance between two longitudinal sides 211 and 213. Inlets 221 and 222 channel the liquid or fluid to the central zones 223 and 224 of the stators, the configurations of the 20 wheels have been previously described, and the action 25 of the vane wheels 207 and 208 of the rotor drives the liquid or fluid towards a common peripheral outlet 225 placed near the median plane 206.

In this embodiment, the liquid or fluid located between two consecutive vanes of a wheel 207 and 208 25 in the intertooth spacings, which is carried when a wheel rotates about its axis 209 or 210 in the slot 214 of the rotor body, is discharged by the oncoming vanes of the wheels 208 or 207 with which it meshes and the discharge liquid or fluid thus cannot be brought back 30 to the inlets of the stators.

Moreover, in this embodiment, there is perfect axial balance. The axial thrust developed by a series of vane wheels is compensated by the axial thrust in the opposite direction developed by the action of the vane 35 wheels of the other series. The bearings 226 and 227, carrying the parts of the shafts 228 and 229 situated on both sides of the rotor body, can thus be light and of simple construction.

In the case of the machine functioning as a pump or 40 a compressor the rotor may be driven at one or both ends of the rotor shaft.

In an alternative embodiment, the vane wheels of such a series provide intertooth spacings which are relatively small compared to the width of the vanes, and 45 it is the vane wheels of the other such series that have vanes of small widths with intertooth spacings sufficiently wide to receive the vanes of the first series of vane wheels.

In an alternative embodiment, the vane wheels are 50 like those shown in FIGS. 19 and 21.

Reference is now made to FIG. 25 and 26. In this embodiment, the rotor 251 comprises a rotor body 252 with two front faces 253 and 254 symmetrically disposed on both sides of a median transverse plane 225. The vanes of a first series of vane wheels 256A, 256B, 256C, 256D, extend from the front face 253, 55 with an operating surface of revolution, or other suitable part. The vanes are housed in slots of the rotor 251 and cooperate with the passages 264a-264d (FIG. 26) of a first stator 257 as previously described, the liquid or fluid entering at 258.

The vanes of a second series of vane wheels 259A-259D extend from the other face 254 of the rotor, also with an annular operating surface of revolution, or other suitable part. The vanes are housed in slots of the rotor 251 and their planes substantially bisect the planes of the slots of the vane wheels 256. The 60 65

vanes of the wheels 259 cooperate with the passages of a second stator 261, symmetrical with the stator 257 in relation to the median plane 255, but with its passages 265a-265d angularly off-set in relation to the vanes of the passages of the rotor 257. As illustrated, there is a 45° off-set. The liquid or fluid enters the stator 261 and 262, through the central part, as in the preceding embodiments.

The discharge of the liquid or fluid caused by the action of the vane wheels 256 and 259 cooperating with the rotors 257 and 261, respectively, takes place only through the outlet 263 near the median plane 255 of the machine.

The shaft 264 of the rotor is carried at its ends by suitable bearings 265 and 266. Also in this embodiment, the axial thrusts developed on the faces of the rotor are directed in opposite directions and serve to balance each other.

Operation of the embodiment of FIGS. 25-26 as a turbine, is illustrated in FIG. 25a-26, where air enters through the duct 258, reaches the central part 271 of the first stator 257, is put under pressure by the action of the vanes of the wheels 256 in the passages 264 and is discharged peripherally into the duct 263 which conveys it towards a combustion chamber (not represented).

The mixture of combustion gases flows through a duct 272, separated from the duct 263 by a partition 273, and is conveyed towards the periphery 274 of the second stator 261, where the expansion exerts its effect upon the vanes of the wheels 259 which cooperate with the passages 265 of the stator 261. Once the expansion is completed, the gases leaving the passages 265 in the center 275 of the stator 261 are evacuated through the exhaust manifold 262.

In alternative embodiments, the cooling may take place through circulation of a fluid, itself cooled by exterior means. Lubrication is obtained through conventional means.

Reference is now made to FIG. 27 and 28. In this embodiment, the rotor 280 comprises a body 281 having a front face 282 from which extends the vanes of two vane wheels 283 and 284, received in a slot 285. The axes of rotation 286 and 287 of the wheels 283 and 284 are in a plane perpendicular to the axis of rotation of the rotor. The wheels 283 and 284 cooperate with one another, their vanes 288 and 289 meshing with one another.

The vanes 288 and 289 of the wheels cooperate with the passages 291a and 291b of stator 292, each of the passages 291 extending over an angular span greater than half the circumference between an inlet end 293 adjacent to the inlet 294 for the liquid or fluid and an outlet end 295 adjacent to the outlets 296 and 297 of the discharged liquid or fluid, which is collected at a single outlet 298. The surface of revolution 278 of the rotor cooperates with incurved mating surfaces of the stator bordering the passages in order to aid sealing.

In this embodiment, the intertooth liquid or fluid is prevented from returning towards the inlet.

Reference is now made to FIG. 29. In this embodiment, the liquid enters the machine through an axial duct 301 of decreasing cross section, this duct housing a propeller 302, mounted on the shaft 303 of the rotor. This arrangement is the same as is shown in my U.S. Pat. No. 3,522,997, and enables the machine to be driven at a very high rotational speed up to several tens

of thousands rpm, with good flow conditions of the liquid or fluid at the intake being preserved.

In the embodiment of FIG. 30, there is shown a compressor in which the inlet 411 for the gas to be put under pressure is at the periphery and the outlet 412 is at the center. The shaft 413 of the rotor is mounted by ball bearings 415 and 416 by a bearing 414 fixed to the casing 410, sealing means 417 are provided between the shaft 413 and the bearing 414. The suction of gas by the vanes 402 of the vane wheels 405, mounted for rotation about axes 409, at the most remote point from the rotor axis 406, is substantially greater than in the embodiment of FIG. 18, which has the advantage of being compact.

Furthermore, the reduction of the height of the passages 407 of the stator 401 provided for putting the gas under pressure, may be less marked than in the previous embodiments, such that the passages still have an appreciable height even at the outlets.

In the embodiment of FIG. 31, a wheel 451 with vanes 452 mounted for rotation about the axis 453 cooperates with the passages 454 of a first stator body 455 symmetrically arranged around a median transverse plane 459 relative to the first body.

The rotor body 461 has a first incurved surface 462 which cooperates with the top faces 463 of the ribs 464 on each side of which are the passages 454 of the first stator body 455. The rotor body 461 has a second incurved surface 465 which cooperates with the top faces 466 of the ribs 467 on each side of which are the passages 456 of the second stator body 457.

The air to be put under pressure enters through an axial inlet 477 which can be protected by a filter 478.

By the movement of the vanes 452 of the wheels 451 in the passages 454 of the first stator body 455, air is compressed and discharged under pressure into a pipe 472 which carries it to a conventional heat exchanger (not shown) when its temperature is lowered. The cooled compressed air is introduced at a peripheral inlet 473 of the second stator body 457 and the cooperation of the vanes 452 of the wheels 451 with the passages 456 of the second stator 457 further increases the pressure of the air which is discharged through a central outlet 474 from which extends an outlet pipe 475. Surface sealing means 476 are provided between the ducts 472 and 473 at the periphery of the body 461.

The shaft 468 of the rotor may have an extension 469 on which a propeller 471 is secured, as shown in dotted lines.

As previously mentioned, the engine of the invention, per se 512 (FIG. 1a) has a configuration similar to that of the compressor 511. It contains a rotor 513, whose shaft 514 extends along the axis of the shaft 44 of the rotor 30 of the compressor 511 and is integral therewith. Vane wheels 516, housed in rotor slots and mounted for rotation around axes 517 tangent to a circumference with its center on the axis 518 common to the shaft 44 and its prolongation 514, protrude from the body 515 of the rotor. The vanes of the vane wheels circulate tightly in the spiral-like passages of a stator 520. In the embodiment illustrated, the entrance of the passages is peripheral and the exit central. The rotor 513 and the stator 520 cooperate tightly through conjugated surfaces of revolution.

The air entering the compressor 511 through the entrance 24 is put under pressure when the said compressor is operating, the pressure ratio can then reach a

value superior to that of conventional gas compressors. The compressed air emerging through the duct 39 is admitted into a combustion chamber 523. Fuel is introduced into the combustion chamber through an injection device 524. If necessary, particularly to start the engine, an ignition device, as spark plug 525, may be provided.

The mixture resulting from the combustion, being at a high temperature, is admitted through the peripheral entrance 526 of the engine per se 512 and is expanded in the passages of the stator 520 and, pushing the vanes of the vane wheels 516, puts the rotor 513 into rotation. The effective work is collected on the rotor shaft 514. Moreover, the rotor shaft is used to power the compressor 511.

Reference is now made to the embodiment of the invention illustrated in FIG. 32. In this embodiment, the engine comprises a compressor 601 and an engine per se 602, of the same general configuration as in the previously described embodiment of FIG. 1a. However, here the wheels 603, mounted for rotation around axes 604, have their vanes 605 circulating on one side in the spiral-like passages 606 of the stator 607 of the compressor 601 and on the other side, in the spiral-like passages 608 of the stator 609 of the engine 602. The body 610 of the rotor has on one side, a first incurved surface of revolution 611 about the axis of rotation 612 of the rotor, and which cooperates with the top surfaces 613 of the ribs 614 separating adjacent passages of the stator 607.

The body of the rotor 610 has on the other side, facing the stator 609 of the engine, another incurved surface of revolution 615 around the axis 612, and which cooperates with the top surfaces 616 of the ribs 617 bordering the passages 608 of the stator 609 contributing to seal said passages.

The shape of the incurved surfaces, 611 and 613 on one hand, and that of the incurved surfaces 615 and 616 on the other hand, may be different from one another, depending upon the processes of compression and expansion that one wants to accomplish respectively in the compressor 601 and in the engine 602.

Advantageously, the air enters the compressor through a central entrance 621, protected by a screen 622, reaches the central opening of the stator 607 of the compressor, is compressed by the circulation of the vanes 605 of the wheels 603 in the spiral-like passages of the stator 607, and is discharged under pressure through the peripheral duct 624 into a combustion chamber 625.

The said chamber 625, presents an interval liner 626 in which the fuel is admitted through a fuel system 627 and the mixture of air and fuel, which can be ignited by an ignition system 628 or by the temperature elevation due to the pressure rise alone, produce high temperature combustion gases, which are mixed up with a portion of the compressed air having followed the peripheral circuit 629 of the chamber. The combination reaches, through a peripheral admission manifold 631, the stator 609 of the engine 602, where the internal energy of hot gases is utilized to transmit motion, by direct action upon the vanes 605 of the wheels situated in the passags 608 of the stator 609, to the rotor 610 bearing said wheels. The gases, leaving the passages 608 in the central part of the stator 609, are evacuated through an exhaust manifold 632.

The effective work is collected on the shaft 633 of the rotor 610 journalled in suitable bearings 634 and 635.

In an alternative embodiment, the shaft 633 comprises a prolongation 636 (shown in dotted line) to which are secured the blades 637 of an inducer 638 to pre-compress the air admitted into the compressor 601.

Reference is now made to FIG. 33, which illustrates an alternative embodiment particularly well adapted to 10 propulsion of a flying machine. This embodiment is similar to that shown in FIG. 32, except that the shaft 643 of the rotor, journalled in suitable bearings 645, has, at its extremity, an airplane propeller 646. Also, in 15 this embodiment, the exhaust gases of the engine 602 can be canalized in a duct 647 and utilized to obtain propulsion by reaction.

FIG. 34 shows a booster compressor according to the invention which can be used in an internal combustion engine. The compressor comprises a rotor 701, having 20 a body 702 carrying vane wheels 704, mounted for rotation about axes 703. The vanes 705 are engaged in the spiral-like passages 706 of a first stator 707 and they also cooperate with the spiral-like passages 708 of a second stator 709, the stators 707 and 709 being 25 symmetrically disposed relative to a median transverse plane 710 of the rotor 701. The rotor is provided on each side of said plane 710 with incurved surfaces, 711 and 712, respectively, cooperating with the top surfaces of the ribs 713 and 714 separating the adjacent 30 passages 706 and 708 of the stators 707 and 709, respectively.

The exhaust gases of the engine are carried to the central part of the stator 707 via duct 719, and by the 35 expansion of the gases in the passages 706, the vanes 705 are driven, which sets the rotor into rotation. The gases are discharged at the outlets of the passages 706 through the manifold 715.

By the cooperation of the vanes 705 of the wheels 703 with the passages 708 of the stator 709, air outside 40 the machine is sucked in at the periphery of the stator 709 via a duct 716, compressed in the passages by the action of the vanes 705 and discharged under pressure into the central manifold 717 which carries these gases to the engine.

Referring now to FIG. 35, there is illustrated an alternative embodiment of a rotative gas engine constructed according to the invention. Through a peripheral entrance 801 of a stator 802, the air reaches a compressor 803 which comprises said stator and vane wheels 804 of a rotor 805. The vanes 806 of said wheels cooperate 50 with spiral-like passages 807 of the stator 802 to compress the air, which, at the exit of said passages, is collected by a central duct 809, to which is connected to a manifold 810. The said manifold conveys the compressed air to the entrance of a combustion chamber 811. Part of said air penetrates into an interior liner 812, where the fuel, ignited by spark plug 814, is admitted through the nozzle 813. The burning gases, leaving the liner 812, are mixed with part of the compressed air circulating in the interval 816 and the mixture is admitted into the central part of the stator 819 of the rotative engine 817 which comprises the same wheels 804 with 55 vanes 806, the same vanes which cooperate with the passages 818 of the stator 819. The rotor 805 has on each side of the mean cross plane 820 the incurved faces 821 and 822 cooperating with the top surfaces of the ribs, respectively, 823 and 824, which border on 60 65

one hand the passages 807 of the stator 802, and on the other hand the passages 818 of the stator 819. The expansion of hot gases in the passages 818 pushes the vanes 806, which through the wheels 804 comprising those vanes, put into rotation the rotor 805 and the shaft 825 affixed thereto, and on which the energy is collected. The shaft 825 is set in suitable bearings 826 and 827.

In these different embodiments, it will be seen that the same vanes, during one part of their displacement, compress the air, and during the other part of their displacement, receive the motive action of hot gases. Thus, the vanes operate at optimal conditions, especially as regards their cooling, each vane being alternately submitted to the action of hot gases and relatively fresh air.

Reference is now made to FIGS. 36 and 37. The rotor 950 as here embodied, formed as a one-piece body 951, includes on one of its front faces, an incurved surface of revolution 953 adapted to cooperate with the top surfaces of the ribs of the facing stators in order to ensure the sealing of the stator passages. A vane wheel 955 is adapted to cooperate simultaneously with passages of the first stator and with the passages of the second stator. In this embodiment, the body 951 of the rotor has large longitudinal slots 954 regularly angularly off-set, and each slot houses a vane wheel system comprising, apart from the vane wheel 955 with its shaft 956, sealing plates 957 and 958, urged against the wheel surfaces by springs 959 and 960 which are supported at their ends by plates 961 and 962 urged against the surfaces 963 and 964 of the slots.

After the wheel systems have been placed in the slots, the openings of the slots are sealed by a ring 965 fixed to the body 951 by bolts 966.

FIG. 38 shows an embodiment similar to FIG. 25, except that there are provided two rotors and four stators. In this embodiment, each series of vane wheels housed in each of the rotors cooperates on the left with a first stator and on the right with a second stator. Here, there is shown a typical vane wheel 1001 of the first rotor cooperating with stators 1002, 1003 and a typical vane wheel 1004 of the second rotor cooperating with stators 1005, 1006. All other parts are the same as previously described.

FIG. 39 is similar to FIG. 25, except that the stator 261 is constructed with a floating disc 261a biased by washer spring 261b into engagement with vane wheel 259 and is suitably sealed by O-ring 261c. Thus, the rotor 251 housing the vane wheels can move axially on shaft 264 and is pushed by floating disc 261a containing the spiral passageways of stator 261. Advantageously, the working pressure goes behind the disc 261a and, due to the difference of areas on both sides of the disc, pushes the latter against the rotor and by the same token pushes the rotor against the first stator 257. At starting conditions, or if the pressure is not high enough, washer spring 261b does the same job. O-ring 261c prevents leakage to the inlet or low pressure side of the machine.

It will be understood that the number of vane wheels in a rotor as well as the number of vanes of a wheel may be different from those illustrated in the drawings. The configuration of the stator is adapted to that of the wheel and the vanes.

Also, the stator surface provided with the passages may have an enclosed shape, so that the vanes cooper-

ate with the passages of the stator over an angular span greater than the path of the vane wheels. In such an embodiment, the stator may be formed in several parts, assembled along transverse or diametral planes.

It will also be understood that the invention relates to an embodiment in which the spiral-like passages are made in the turning part, the vane wheels being then mounted for rotation in the stationary part.

It will be understood that the part with the passages of the machine as well as the part with the vane wheels are mounted for rotation around a common axis.

Also, the various embodiments of the machine of this invention are adapted to operate as hydraulic motors. For example, in the first described embodiment, illustrated in FIG. 1, the liquid under pressure is introduced through the tube 24 into the chamber 28; the thrust exerted by the liquid on the vanes 69 housed in the passages 91 sets the rotor 30 in rotation; the wheels 62 with vanes 69 rotate about their axis 71. The liquid is discharged through the pipe 39 extending from the space 37 in the casing 29.

The liquid under pressure may also be introduced through the pipe 39 and after driving the rotor 30 through the intermediate of the vanes 69 of the wheels 62, discharged through the tube 24.

The invention in its broader aspects is not limited to the specific embodiments herein shown and described but departures may be made therefrom within the scope of the accompanying claims, without departing from the principles of the invention and without sacrificing its chief advantages.

What is claimed is:

1. A positive-displacement machine in which the conversion of pressure energy of fluids is obtained by the circulation of at least two spaced vane members in at least one spiral-like passage of revolution defined by a pair of rib members having top surfaces and side walls, wherein

said vane members are parts of at least two vane wheels,

each of said vane wheels being mounted for rotation about its own axis and housed in a slot formed in a first part of said machine,

said vane members circulating in said spiral-like passages of revolution formed in a second part of said machine.

at least one of said first and second parts of said machine is rotatable, the axis of rotation thereof constituting the main axis of rotation of said machine, said spiral-like passages of revolution being generated by a combined rotation of said vane members about the axis of rotation of their respective vane wheels and by rotation of said first part of said machine in relation to said second part of said machine,

said spiral-like passages being closed across the top of said side walls by a curved surface of revolution formed on said first part of said machine receiving said vane wheels,

said curved surface of revolution formed on said first part of said machine cooperating with a conjugated surface of revolution formed on the top surfaces of said ribs defining said passages on said second part of said machine,

said defined spiral-like passages of revolution having an inlet and an outlet and a continuous progres-

sively varying cross-sectional area from the inlet to the outlet thereof, each of said curved surface of revolution and said conjugated surface of revolution being generated about said main axis of rotation of said machine, whereby the ratio and the gradient of compression or expansion for a compressible fluid, and the constant volume flow for an incompressible fluid, flowing through said passages between said two spaced vane members circulating therein are imposed by the relative position and configuration of said co-operating conjugated surface of revolution to said curved surface of revolution generated by the rotation of said vane members about said main axis, of said machine and by the difference of the distances of said vane members from said main axis of said machine during their travel from the inlet to the outlet of said spiral-like passages.

2. A machine as claimed in Claim 1, wherein said continuous progressively varying cross-sectional area of said defined spiral-like passages of revolution comprises passages of continuous progressively varying depth.

3. A machine as claimed in claim 1, wherein at least one part having said spiral-like passages is a rotor and at least one part carrying said vane wheels is a stator.

4. A machine as claimed in claim 1, wherein the planes in which said vane wheels rotate are angularly inclined with respect to the axis of rotation of said machine.

5. A machine as claimed in claim 1, including sealing means provided in the top surfaces of said ribs defining said passages cooperating with said machine part carrying said vane wheels for sealing said passage compartments.

6. A machine as claimed in claim 1, including means for biasing said machine part provided with said spiral-like passages into engagement with said machine part carrying said vane wheels.

7. A machine as claimed in claim 1, wherein said vane wheels are each formed of two opposed, identical, longitudinal half-sections.

8. A machine as claimed in claim 7, including spring means biasing the longitudinal sides of said vane members against the sidewalls of said passages.

9. A machine as claimed in claim 1, wherein said first part of said machine is a rotor the axis of rotation of which constitutes said main axis of said machine, and said second part is a stator, which is stationary.

10. A machine as claimed in claim 9, wherein said spiral-like passages of revolution are formed in said stator so as to extend substantially only on a side of said rotor.

11. A machine as claimed in claim 9, wherein said rotor has said at least two vane wheels, said at least two vane members of said vane wheels circulate on one side of the rotor in at least one spiral-like passage of a first stator and also on the other side of said rotor in at least one spiral-like passage of a second stator, the cooperating surfaces of revolution of the first side of said rotor

sages of said first stator and the corresponding cooperating surfaces of revolution on the other side of said rotor are chosen so that, in relation to the distances of the passages from the main axis of the rotor and in relation to the surface of revolution generated by said vane members when rotating about said main axis of the ma-

chine, the volume-rate of flow at any cross-section of the passage in both said first stator and said second stator is constantly changing.

12. A machine as claim in claim 11, wherein said rotor has on one side at least two vane wheels cooperating with said first stator and on the other side at least two other vane wheels cooperating with said second stator.

13. A machine as claimed in claim 13, wherein said vane wheels on said one side of said rotor are aligned with said other vane wheels on said other side of said rotor, and each aligned pair of vane wheels is housed in a single slot and mounted with their respective vane members engaged in meshing relationship.

14. A machine as claimed in claim 9, wherein said rotor has said at least two vane wheels protruding on one side thereof and said at least two vane members circulate on one side thereof and said at least two vane members circulate in at least one spiral-like passage formed in the adjacent stator, and the cooperating surfaces of revolution formed on said rotor and on the top surfaces of said ribs defining said passages on the stator are arranged in such a way in relation to the variation of distances of said passages from the main axis of said machine that the volume-rate of flow at any cross-sectional point of said passage is constant.

15. A machine as claimed in claim 14, including two of said rotors and four of said stators, wherein each of said rotors has at least two vane wheels cooperating with two of said stators.

16. A machine as claimed in claim 14, including two of said rotors and four of said stators, wherein each of said rotors has on both sides thereof at least two vane wheels which cooperate with a stator.

17. A machine as claimed in claim 9, wherein said cooperating surfaces of revolution formed on said rotor and on the top surfaces of said ribs defining said passages on the stator are arranged in such a way in relation to the variation of distances of the said passages from the main axis of the machine as to give a continuous variation of the volume-rate of flow when the vane members move along said passage.

18. A machine as claimed in claim 17, including two of said rotors and four of said stators, wherein each of said rotors has on both sides thereof at least two vane wheels which cooperate with a stator.

19. A machine as claimed in claim 17, including two of said rotors and four of said stators, wherein each of said rotors has at least two vane wheels cooperating with two of said stators.

20. A machine as claimed in claim 9, wherein said rotor has said at least two vane wheels, said at least two vane members of said vane wheels circulate on one side of the rotor in at least one spiral-like passage of a first stator and also on the other side of said rotor in at least one spiral-like passage of a second stator, the cooperating surfaces of revolution formed on the first side of said rotor and on the top surfaces of the ribs defining said passage of said first stator and the corresponding cooperating surfaces of revolution on the other side of said rotor are chosen so that, in relation to the distances of the passages from the main axis of the rotor and in relation to the surfaces of revolution generated by said vane members when rotating about said main axis of the machine, the volume-rate of flow at any cross-section of the passage in both said first stator and said second stator is constant.

65

21. A machine as claimed in claim 20, wherein said rotor has on one side at least two vane wheels cooperating with said first stator and on the other side at least two other vane wheels cooperating with said second stator.

22. A machine as claimed in claim 21, wherein said

vane wheels on said one side of said rotor are aligned with said other vane wheels on said other side of said rotor, and each aligned pair of vane wheels is housed in a single slot and mounted with their respective vane members engaged in meshing relationship.

UNITED STATES PATENT AND TRADEMARK OFFICE
CERTIFICATE OF CORRECTION

PATENT NO. : 3,904,331

Page 1 of 5

DATED : September 9, 1975

INVENTOR(S) : Eugeniusz M. Rylewski

It is certified that error appears in the above-identified patent and that said Letters Patent are hereby corrected as shown below:

In the drawings, Sheets 3 and 4, Figs. 9 and 10, reference numerals 92c and 92d should be added at the points where passages or lines 91c and 91d intersect the circular line 93, respectively; reference numerals 94b, 94c, 94d should be added at the points where passages or lines 91b, 91c and 91d, respectively, intersect circular line 95. Sheet 4, Fig. 10, delete reference numeral 94. Sheet 12, Fig. 27, underline reference numerals "283" and "284" located on the vane wheels; change reference numeral "284" connected with the arrow to -- 285 --.

Column 1, line 38, "roation" should read -- rotation --; line 40, "passges" should read -- passages --; line 43, "frm" should read -- from --; line 54, "centrifgual" should read -- centrifugal --; line 64, "passage" should read -- passages --.

Column 2, line 7, "discshaped" should read -- disc-shaped--; line 13, "pasages" should read -- passages --; line 24, "hihg" should read -- high --; line 28, "compressions" should read -- compression --; line 46, "roational" should read -- rotational --; line 53, before "driving" insert -- a --.

Column 3, line 4, "form" should read -- from --; line 45, "centrigual" should read -- centrifugal --.
